Des. 211,120
Patented May 21, 1968

211,120

LANTERN HOLDER

Delmar D. Sherbert, 902 N. 11th St.,
Salina, Kans. 67401

Filed Sept. 19, 1967, Ser. No. 8,654

Term of patent 14 years

(Cl. D48—4)

Fig.2.

Fig.1.

Fig.3.

Fig.4.

FIG. 2 is a top plan view thereof;

FIG. 3 is a rear elevational view thereof; and

FIG. 4 is a fragmentary side elevational view thereof, the hook portion of the lantern holder being shown in an extended position.

I claim:

The ornamental design for a lantern holder, as shown and described.
